UNITED STATES PATENT OFFICE.

ALFRED DUNHILL, OF LONDON, ENGLAND.

METAL MATCH-BOX.

1,218,382.

Specification of Letters Patent.

Patented Mar. 6, 1917.

Application filed October 30, 1916. Serial No. 128,490.

To all whom it may concern:

Be it known that I, ALFRED DUNHILL, a subject of the King of Great Britain and Ireland, residing at 28 and 30 Duke street, 5 St. James's, London, S. W., England, have invented new and useful Improvements in Metal Match-Boxes, of which the following is a specification.

The invention relates to metal boxes for holding matches and to that particular variety of box which consists of an inner tray or container for the matches, a housing surrounding said tray or container, an outer part snugly fitting the exterior of and 10 hingedly connected to said housing, and means by which said tray or container will be pushed out to the required extent when the outer part of the box is turned outward and be retracted when said outer part is 15 turned back. The outer parts of such boxes serve as wind shields.

A defect of such boxes, as hitherto constructed, is that the inner trays or containers thereof can not be pushed into the housings 20 of the boxes without causing the outer parts of the boxes to be also retracted, in other words the outer parts of said boxes can not in such circumstances be used as wind shields.

According to the present invention the mechanism by which the inner tray or container, hereinafter referred to as the tray, of a box of the above described kind is pushed out and retracted is such that it will 25 allow the tray to be pushed into the housing of the box without causing the outer part of the box to be returned to its normal position.

The invention is illustrated by the accompanying drawings:—

Figure 1 is a side elevation illustrating the external appearance of the improved box. Fig. 2 is a view corresponding to Fig. 1, but showing in dotted lines mechanism which, in addition to causing the tray of the box 45 to be pushed out and retracted when the outer part of the box is turned outward and back, will allow the tray to be pushed in by hand without causing movement of the outer part of the box. Fig. 3 is a transverse section of Fig. 2, taken on the line *a*—*b*. Fig. 4 is a plan, viewed from below, of the tray 50 of the box. Fig. 5 is a view corresponding to Fig. 4, illustrating a slight modification.

1 is the tray of the improved box. 2 is a housing for the tray 1. 3 is the outer part of the box which is hingedly connected to the

housing 2 and when turned outward causes the tray 1 to be pushed out to a limited extent and when turned backward retracts said tray.

All of the above enumerated parts are common to the type of box to which the invention relates.

In the case of the present invention the mechanism through the medium of which 65 the tray of the box is pushed out and retracted is such as to allow the tray to be pushed in by hand without causing the outer part of the box to be returned to its normal position.

A match box fulfilling this purpose may be constructed in the manner now to be described.

The outer part 3 of the improved box is hingedly connected to the housing 2 by 75 means of a long rivet 4. A lever 5, provided at its outer end with an upstanding pin 6, is loosely mounted on the rivet 4 below the tray 1, and the rivet is surrounded by a sleeve 7 which extends from the inner face 80 of the lever 5 to the inner face of the opposite wall of the housing 2. The lever 5 is connected to the outer part 3 of the box by a pin 8, and the housing 2 is formed with an arc-shaped slot 9 in which the pin 8 travels 85 as the outer part 3 of the box is turned outward. The tray 1 is provided on its bottom with a cam groove 10, 11 of substantially L-shape, in which engages the upstanding pin 6 of the lever 5, with a recess 12, located in 90 front of the cam groove 10, 11 and separated therefrom by a wedge-shaped projection 13, and with a gateway 14 connecting the innermost part of the cam groove 10, 11 to the recess 12. The first part 10 of the cam groove 95 10, 11 is arc-shaped, is struck from the center of the rivet 4, and is made of such length that there will be no movement of the tray 1 until the outer part 3 of the box has been moved into a position which will allow the tray 1 to move outward. The second part 11 of the cam groove 10, 11 is such that as the movement of the outer part 3 of the box is continued the tray 1 will be forced outward until at the end of the movement of 100 105 the outer part 3 of the box, when said part will have been turned through a right angle, the tray 1 will have been pushed out to the required extent. The wedge-shaped projection 13 is provided opposite to the inner end 110 of the curved or first part 10 of the cam groove 10, 11 with an incline 15 to allow the

pin 6 at the end of the lever 5 to pass on to the wedge-shaped projection 13 when the outer part 3 of the box is being turned back. The recess 12 may be of segmental shape, as shown in Fig. 4, or extend to the front of the tray 1, as shown in Fig. 5.

The cam groove 10, 11, the recess 12, the arc-shaped projection 13 and the gateway 14 are preferably constructed by means of 10 stampings or plates 1' and 1'', of the necessary shape, Figs. 4 and 5, secured to the bottom of the tray 1. The side wall of the housing 2 which is normally covered by the outer part 3 of the box is provided with a 15 roughened or striking surface for the matches.

The above described parts coöperate as follows:—

Assuming that the box is closed and the 20 user wishes to abstract a match then the outer part 3 of the box is turned outward. During the first part of this outward movement the tray 1 will remain in the housing 2, as the pin 6 on the outer end of the lever 25 5 will be traveling in the arc-shaped part 10 of the cam groove 10, 11. As soon as the outer part 3 of the box has been turned into a position which will allow the tray 1 to be pushed out the pin 6 will enter the second 30 or straight part 11 of the cam groove 10, 11. Further movement of the outer part of the box will cause the tray 1 to be pushed out to the required extent. A match having been 35 withdrawn from the box the tray 1 is pushed in by hand. This movement of the tray is possible as the pin 6 will be opposite to the gateway 14 and can therefore pass into the recess 12. The match having been struck on the roughened surface provided on the outer 40 wall of the housing 2, below the outer part or wind shield 3, the box is closed by turning back the outer part 3 of the box. At the commencement of the backward movement of the outer part 3 the pin 6 at the outer end 45 of the lever 5 will be in line with the gateway 14. During the first part of said movement the pin 6 will travel in the recess 12, but during the latter part of the movement will ride up the incline 15, pass over the 50 wedge shaped projection 13 and snap into the arc-shaped part 10 of the cam groove 10, 11. Eventually the pin 6 will travel to the end of the arc-shaped part 10 of the cam groove 10, 11, that is to say reach its initial position.

What I claim as my invention and desire 55 to secure by Letters Patent of the United States is:—

1. A match box, comprising a housing, a wind shield pivoted to the housing, a tray for the matches slidable in the housing, and 60 lever mechanism operatively connecting the tray with the wind shield and engaging positively with the tray in one direction and operating to slide the tray outwardly when the wind shield is raised, said mechanism 65 being automatically disengageable in the reverse direction to permit the tray to be pushed in without lowering the wind shield.

2. A match box, comprising a housing, a wind shield pivoted to the housing, a tray 70 for the matches slidable in the housing and provided with an actuating device and an inclined portion arranged near one end thereof, a lever connected with the wind shield at one end and having a projection at 75 its other end for engaging with the said device and inclined portion, said device operating to slide the tray outwardly while the wind shield is being raised, and said inclined portion operating to disengage the said lever 80 to permit the tray to be pushed in without lowering the wind shield.

3. A metal box for holding matches, consisting of a tray, a housing surrounding said tray, an outer part, shaped to serve as a wind 85 shield, snugly fitting and hingedly connected to said housing by means of a rivet, a lever loosely mounted on said rivet at a level below said tray, a pin connecting said lever to said outer part or wind shield, an arc-shaped slot formed in said housing for the travel of said pin, an upstanding pin at the outer end of said lever, and a cam groove of substantially L-shape, a recess in front of 90 said cam groove separated from said cam groove by a wedge-shaped projection formed on its front with an incline in line with the outer part of said cam groove, and a gateway connecting the inner end of said cam groove to said recess, said cam groove, recess and gateway being provided on the bottom of the tray of the box and coöperating with the upstanding pin at the outer end of said lever, substantially as described.

In testimony whereof I have signed my 105 name to this specification.

ALFRED DUNHILL.
